UNITED STATES PATENT OFFICE.

ARTHUR D. LIGHTNER AND EDWARD HOLMES, OF TOLEDO, OHIO, ASSIGNORS TO THE WILLYS-OVERLAND COMPANY, OF TOLEDO, OHIO, A CORPORATION OF OHIO.

HOISTING APPARATUS.

Application filed January 18, 1919. Serial No. 271,835.

To all whom it may concern:

Be it known that we, ARTHUR D. LIGHTNER and EDWARD HOLMES, citizens of the United States, residing at Toledo, county of Lucas, and State of Ohio, have invented certain new and useful Improvements in Hoisting Apparatus, of which we declare the following to be a full, clear, and exact description.

- 10 This invention relates to improvements in hoisting apparatus, and more particularly hoisting apparatus for use in connection with the loading and double-decking of automobiles in freight cars. Although the device is particularly designed for use in connection with motor vehicles, yet it is to be understood that it may be used for other purposes for which it is found to be adapted.
- 15 One object of this invention is to provide a simple and economical form of equalizing means, which is automatic in its operation and efficient in operation for maintaining a hoisting platform in horizontal position at all times while in use.

A further object of this invention is to provide fluid operated hoisting and equalizing means which will be of simple construction and efficient in operation.

- 20 A further object of this invention is to provide an improved construction for controlling at all times the various parts of the lifting platform and maintaining the same in a proper horizontal position.

- 25 Further objects of this invention relate to economies of manufacture and details of construction, as will hereinafter appear from the detailed description to follow.

- 30 We accomplish the objects of our invention in one instance by the devices and means described in the following specification, but it is evident that the same may be varied widely without departing from the scope of the invention as pointed out in the appended claims.

35 A structure constituting one embodiment of our invention, which may be the preferred, is illustrated in the accompanying drawing, forming a part hereof, in which:

Figure I is a top plan view of the improved hoisting apparatus.

Figure II is an end elevation of the structure shown in Figure I.

40 Figure III is a detail, diagrammatic view

showing the manner of attaching the ends of the cable to the movable frame and to the stationary frame portions, and the relative positions of the pulleys.

Figure IV is a side elevation of the structure shown in Figure I, illustrating the position of the automobile wheels relative thereto, when an automobile is supported upon the hoisting frame.

Figure V is a detail horizontal plan view showing the manner of positioning the inner pulleys with respect to that portion of the stationary frame to which they are attached, taken on the line V—V of Figure IV.

Figure VI is a vertical sectional view taken along the line VI—VI of Figure IV.

Figure VII is a vertical sectional view taken along the line VII—VII of Figure I.

Figure VIII is a vertical sectional view taken along the line VIII—VIII of Figure I.

Figure IX is a vertical sectional view taken along the line IX—IX of Figure I.

Figure X is a plan view of the pipe for conducting fluid to the various cylinders.

In the drawing, similar reference characters refer to corresponding parts throughout the several views, and the sectional views are taken looking in the direction of the small arrows at the ends of the section lines.

In carrying out our invention we provide a loading dock or platform having a pair of parallel rails therein, which are substantially as far apart as the usual tread of an automobile. These rails are supported by lifting cylinders located beneath the platform so that they may be lifted to elevate an automobile which has been run thereon. When the automobile has been lifted a substantial distance above the loading platform, a loading truck may be run beneath it and the rails lowered to allow the automobile to rest upon the truck. The automobile resting on the truck may then be transferred to any desired point, such as within a freight car, when the automobile is to be placed therein for shipment.

Referring to the numbered parts of the drawing, a plurality of fluid pressure cylinders 10, preferably four in number, are secured in position upon a foundation, and are each provided with a piston 12, carrying upon one end a piston head 13 fitting

closely within the interior of the cylinder. The main fluid supply pipe 14 is provided with a plurality of branches 15 communicating with each of the above mentioned cylinders through an opening 16 formed in the lower cylinder head 17 of each cylinder. Each of the cylinders above described is provided with an upper cylinder head 18 containing an opening therein for the reception of the piston rod 12. The above described cylinders, of which there may be one for each corner of the movable frame, rest upon the foundation, and have firmly secured to their upper ends a stationary frame, designated generally by the numeral 19, and which comprises a pair of longitudinal members 20, each of which is secured at its opposite ends to the upper portions of the side cylinders by means of split bearings 21 firmly secured together by bolts 22. A pair of transverse frame members 23, which may be formed of angle iron, are properly secured to each horizontal frame member 20 at points near the centers of said horizontal frame members, the said transverse members 23 supporting a small platform 24, which platform in turn carries various operating parts that will be described hereinafter.

30 A pair of rails 25 provided with upwardly extending flanges 26, and downwardly extending flanges 27, are secured at each end by pins 29 to the upper ends of the piston rods located on one side of the machine for pivotal connection therewith. Each of the rails 25 is provided at its ends with a plurality of openings 30, formed in the base portion thereof, for the reception of pins 31 carried by blocks 32. The said blocks are formed in such a manner to fit within the upwardly extending flanges of the rails 25, so that the pins carried by each block may be engaged with any one of the openings 30. As shown in Figure IV, the purpose of these blocks is to hold the wheels of the automobile in such a position as to prevent movement of the automobile when in position upon the rails.

50 Each of the rails 25 is also provided at a point near one end with a pair of slots 33 formed in the upwardly extending flanges 26 providing means of attachment for securing the portions 34 of a strap to the upwardly extending flanges, whereby the straps may be passed over the rims of the automobile wheels and secured together by a buckle 35. By the provision of these fastening means the automobile is firmly secured in position upon the rails when it is being raised. Buffer rods 36 are attached to each of the rails at points near the points of attachment of the piston rods thereto, as indicated at 37. Each of these rods is slidably positioned between one of the longitudinal members 20 and a corresponding mem-

ber 21 and carries upon its lower end an enlarged portion 38 adapted to strike against the lower edges of the corresponding members 20 and 21 to limit the upward movement of the frame.

55 Mounted upon the platform 24 is a fifth fluid operated cylinder 40 provided with upper and lower cylinder heads 41 and 42 respectively, and carrying a piston rod 43 provided with a piston head 44 fitting closely within the interior of the cylinder. The lower flanged edge of the cylinder head 41 rests upon the upper surface of the platform 24, and the cylinder is retained in proper position on the platform, by means of a plate 45 resting upon the upper surface of the cylinder head 41 and connected to the platform by bolts 46. The lower end of the piston rod carries a plate 47 firmly secured thereto, and provided with down-turned portions 48 connected by a pin 49; and a multiple grooved pulley 50 is mounted to freely rotate on the pin 49.

60 Secured to each of the longitudinally extending rails at points near the ends thereof, is a pair of flexible cables 52, each of which is attached to a rail by being connected to a pin 53 passing through the down-turned flanges of the rails. A pair of longitudinal base frame members 54 extend between the lower portions of the side cylinders upon each side of the device, and are firmly secured in any suitable manner to the foundation. Upwardly converging braces 69 may be employed for connecting the longitudinal base frame members 54 to the upper horizontal frame members 20 to give greater rigidity to the structure. Mounted upon each of the longitudinally extending base frame members 54 at points near the ends thereof, are brackets 55. Each of the brackets carries a pin 56 upon which is rotatably mounted a pulley 57. Brackets 58, one for each cable to be used, are mounted upon the lower face of the platform 24 and secured to the platform in any suitable manner as by bolts or rivets 59. Each of the brackets 58 carries a sheave or pulley 60 rotatably mounted therein in any suitable manner, as upon a pin 61. A plurality of eye-bolts 63, one for each cable to be used, are secured to the platform by means of nuts 64 and positioned upon opposite sides of the control cylinder 40. Each of the cables 52, of which there is preferably employed one for each corner of the device, is secured to the end of each longitudinally extending rail and passes downwardly and under one of the pulleys 57, one of said pulleys being secured to one of the lower base frame members 54, at each corner of the device, then upwardly and over a corresponding pulley 60 mounted upon the lower face of the platform 24, then downwardly and over a grooved pulley 50, which is preferably provided with the same number of grooves

upon its surface as there are cables used, and from this pulley each cable passes upwardly and is attached to one of the eye-bolts 63 secured to the platform 24. One end of each cable is attached at each corner of the rectangular shaped movable frame, which comprises the flanged rails 25, and passes in a diagonal direction toward the center of the frame, over the pulleys 57 and 60, where each of the cables passes over the common pulley 50, thence upward for attachment to a fixed portion of the frame and thus equalizing means is provided which insures that all portions of the frame will travel at the same rate of speed in moving upwardly or downwardly. The upper cylinder head of the central cylinder 40 is provided with an opening for the reception of a branch portion 67 of the fluid supply pipe which supplies fluid pressure to the main lifting cylinders 10 of the device.

Thus when pressure is applied to the main pressure cylinders 10, such pressure is applied to the central cylinder 40 to hold the grooved pulley 50 firmly against the various cables for the purpose of exerting sufficient tension upon the cables to equalize the movement of the frame. Since the cables are of equal length, when it is desired to maintain the movable platform in a horizontal position during its raising and lowering movement, any tendency for one end of the movable platform to advance faster than the other will tend to raise the central piston, whereupon less tension will be exerted upon the cables connected to the other end of the frame and consequently the resistance acting against upward movement of the other end of the movable frame will be diminished. It will be noted that the area of the piston head in the central cylinder 40 is considerably less than the area of either of the piston heads in the lower upright cylinders 10 and the counter-acting pressure exerted by the cylinder 40 is evenly distributed between the cylinders at the corners of the device, thus the counteracting pressure exerted by the central cylinder does not materially affect the lifting force exerted by the upright corner cylinders.

While it is understood that this particular embodiment of hoisting apparatus may be applied to a variety of different uses, it has been found to be particularly adapted for use upon a dock where it is desirable to raise an automobile to elevated position for the purpose of placing it upon the elevated frame of a truck. Devices providing no means for equalizing the movement of the platform are found to be objectionable for the purpose since it is difficult to so position an automobile upon the movable frame as to evenly distribute the weight of the automobile. It has been found that a tendency exists for one end of the movable frame to travel more

rapidly than the other with a consequent danger of the parts of the hoist becoming jammed, while the automobile is dangerously tilted as it is moved upwardly. This is particularly true in fluid operated hoisting apparatus since they are so designed as to exert an equal amount of pressure upon each corner of the movable frame.

In the normal position of the hoisting apparatus with respect to the loading dock the longitudinal rails 25 are substantially upon a level with the flooring of the dock when the rails are in a position shown in Figures II and IV of the drawing. The rails 25 are spaced a sufficient distance apart to correspond with the tread of an ordinary automobile whereby the automobile may be readily driven or pushed upon the rails so that it occupies a position thereon as indicated in Figure IV of the drawing. When the automobile has been placed in position upon the rails, the blocks 32 and the straps 34 are placed in position relative to the wheels for the purpose of firmly securing the automobile against movement relative to the rails while it is being elevated. A fluid under pressure, such as compressed air, is then admitted through the main fluid supply pipe 14 and the branch pipes 15 into the corner upright cylinders against the piston heads carried therein. By reason of the fact that the main fluid supply pipe 14 communicates freely with the various branches 15, the pressure is communicated equally to each of the four upright corner cylinders and against the lower faces of the piston heads carried therein.

Simultaneously with the admission of fluid pressure to the four corner cylinders, pressure will also be admitted to the central cylinder 40 through the branch pipe 67, communicating therewith. The degree of fluid pressure exerted upon the central cylinder is capable of control by means of the valve 70 located in the branch pipe 67 so that the downward pressure exerted upon the upper face of the central piston head may be increased or diminished as desired. In any event the amount of pressure exerted upon the central piston head 44 will be equally distributed among the four corners of the movable platform, so long as the platform continues to maintain itself in a horizontal plane while it is being raised. If, however, one end of the platform by reason of an unequal distribution of weight thereon begins to move upwardly more rapidly than the other end of the platform, the cables attached to that end of the platform which is moving more rapidly will be drawn more tightly against the pulley 50 and tend to force the same upwardly against the fluid pressure upon the top of the cylinder or piston head 44. This naturally causes a corresponding loosening of the cables at

tached to the other end of the movable frame, and consequently, less resistance to the upward movement of that end of the frame, until a point of equilibrium is reached to put the frame in a substantially horizontal position.

When the automobile has been raised a sufficient distance, a truck provided with an elevated frame may be placed beneath the automobile, the air pressure upon the lower faces of the piston heads 13 may be reduced to permit the automobile to be lowered from the truck in such a manner that the front and rear axles will be supported thereby, and the automobile can be transported thereon to any desired point. It will be seen that in lowering the automobile upon the truck, the equalizing mechanism will be effective in the same manner as in elevating the automobile for the purpose of maintaining the movable frame and the automobile carried thereby in proper horizontal position during the lowering movement. After the automobile has been placed upon the truck in the manner described above, it can be released from the movable frame and the source of fluid pressure may be disconnected to permit the movable frame to resume its initial position, as shown in Figs. II and IV. The rods 36 extending from the down-turned flange portion of the rails 25 and provided with enlarged members 38 at their lower end are adapted to prevent raising the frame beyond a predetermined point when pressure is exerted upon the pistons.

While the equalizing mechanism is designed primarily for the purpose of maintaining the movable platform in a horizontal position at all times, it is obvious that it may be used, if desired, for the purpose of maintaining the platform at a given angle to the horizontal during its raising and lowering movements. By providing cables extending to one end of the movable platform of less length than the cables extending to the other end of the movable platform, the platform may be tilted in such a manner as to form a slight angle with the horizontal end to be maintained during its raising and lowering movement in planes parallel with the plane in which it was originally arranged.

By the use of the structure described the movable frame is maintained in a horizontal plane at all times or in other words in a plane parallel to a given horizontal plane at all times while it is being raised and lowered. If it is desired to use this device with the frame tilted at a slight angle to the horizontal the equalizing mechanism shown and described will serve to maintain the frame at all times at substantially the same angle to the horizontal, or in other words, the frame will be maintained at all times, while it is being raised and lowered, in a plane

substantially parallel to a given plane. By reason of there being a cable attached to a part of the movable frame at each corner of the apparatus the mechanism is not only effective to control the movement of opposite ends of the frame and equalize the same, but also in like manner to equalize the movement of that portion of the frame at each corner thereof. If one corner of the frame starts to move upwardly faster than the others the cable connected thereto will operate in the manner previously described to urge the central piston upwardly and thus by lessening the tension upon the other cables will permit the other corners to move upwardly more freely.

We have shown and described in considerable detail a specific embodiment of our invention, and it is to be understood that this showing and description is illustrative only and for the purpose of rendering our invention more clear, and that we do not regard the invention as limited to the details of construction illustrated or described, nor any of them, except insofar as we have included such limitations within the terms of the following claims, in which it is our intention to claim all novelty inherent in our invention broadly, as well as specifically.

Having thus described our invention, what we claim as new and desire to secure by Letters Patent, is:

1. In an apparatus of the class described in combination, a stationary frame portion, a movable frame portion, means for transmitting movement to the movable frame portion, means for equalizing the movement of the movable frame, and common means for controlling movement of the equalizing means.

2. In an apparatus of the class described in combination, a vertically movable frame, means for imparting movement to the frame, and fluid controlled means for maintaining the frame in a plane substantially parallel to a given plane during its period of movement.

3. In an apparatus of the class described in combination, a vertically movable frame, means for imparting movement to the frame, at a plurality of points, and means radiating from a common point for equalizing the amount of movement of the frame at the several points.

4. In a device of the class described in combination, a movable frame, means for raising and lowering the frame, and fluid controlled means for maintaining the frame substantially horizontal while it is being raised and lowered.

5. In an apparatus of the class described in combination, a movable frame, means for imparting vertical movement to the frame, and means including a system of cables and pulleys radiating from a point adjacent the

center of the frame for maintaining the frame substantially horizontal during its period of movement.

6. In an apparatus of the class described in combination, a movable frame, means for raising and lowering the frame, and fluid controlled means for maintaining the frame substantially horizontal while it is being raised and lowered.
7. In an apparatus of the class described in combination, a movable frame, means for raising and lowering the frame, and pneumatic means for maintaining the frame substantially horizontal while it is being raised and lowered.
8. In an apparatus of the class described in combination, a movable frame, fluid operated means for raising and lowering the frame, means including a system of cables and pulleys for maintaining the frame substantially horizontal during its period of movement, and means for equalizing the tension upon the several cables.
9. In an apparatus of the class described in combination, a movable frame, pneumatic operating means for raising the frame, and means including a system of cables and pulleys radially positioned relative to a common point for maintaining the frame substantially horizontal while in raised position.
10. In an apparatus of the class described in combination, a movable frame, fluid operated means for raising the frame, and fluid controlled means for maintaining the frame substantially horizontal during its period of movement.
11. In an apparatus of the class described in combination, a movable frame, means for raising and lowering the frame, and pneumatically operated controlling means for maintaining the frame substantially horizontal while it is being raised and lowered.
12. In an apparatus of the class described in combination, a vertically movable frame, pneumatically operated means for imparting movement to the frame, and pneumatically operated controlling means for maintaining the frame in a plane substantially parallel to a given plane during its period of movement.
13. In an apparatus of the class described in combination, a movable frame, means for imparting movement to the frame comprising a plurality of pneumatically operated pistons; and means for maintaining the frame in a plane substantially parallel to a given plane during its period of movement, comprising a pneumatically operated piston.
14. In an apparatus of the class described in combination, a movable frame, means for imparting movement to the frame comprising a plurality of pneumatically operated pistons, means for maintaining the frame substantially horizontal during its period of movement comprising a pneumatically operated piston, a pulley carried by said piston, and a plurality of cables co-operating with said pulley.
15. In an apparatus of the class described in combination, a movable frame, means for imparting movement to the frame comprising a plurality of pneumatically operated pistons, means for maintaining the frame substantially horizontal during its period of movement, comprising a pneumatically operated piston, and a plurality of cables co-operating with said pistons.
16. In an apparatus of the class described in combination, a movable frame, means for imparting movement to the frame, and means for constantly maintaining the frame in a plane substantially parallel to a given plane during its period of movement, comprising a pneumatically operated piston, and a plurality of cables co-operating with said piston.
17. In an apparatus of the class described in combination, a movable frame, means for imparting movement to the frame, and means for constantly maintaining the frame in a plane substantially parallel to a given plane during its period of movement, comprising a fluid operated piston, a pulley carried by said piston, and a plurality of cables co-operating with said pulley.
18. In an apparatus of the class described in combination, a movable frame, means for imparting movement to the frame, and means for constantly maintaining the frame in a plane substantially parallel to a given plane during its period of movement, comprising a fluid operated piston, a pulley carried by said piston, and a plurality of cables, each having its ends attached to the movable frame and to the stationary frame and co-operating with said pulley.
19. In an apparatus of the class described, a movable frame, fluid operated means for raising and lowering said frame, and fluid controlled equalizing means for equalizing the movement of said movable frame.
20. In an apparatus of the class described, a movable frame, separate means operable in unison for raising and lowering said frame, and equalizing members controlled from a common point for equalizing the movement of the movable frame.
21. In a device of the class described, the combination of a base, a load carrying frame mounted to move upon the base, means for effecting bodily movement of the frame, said means tending to move that portion of the frame which may have the lighter load faster than the remaining portion, cables connected with the frame at points remote from each other and having their opposite ends anchored upon said base and means for exerting pressure upon all of the cables.

when the load is evenly distributed upon the frame and only upon certain of the cables when the load is unevenly distributed.

22. In a device of the class described, 5 the combination of a base, a load carrying frame mounted to move upon the base, means for effecting bodily movement of the frame, said means tending to move that portion of the frame which may have the lighter 10 load faster than the remaining portion, cables connected with the frame at points

remote from each other and having their opposite ends anchored upon said base and fluid controlled means for exerting pressure upon all of the cables when the load is 15 evenly distributed upon the frame and only upon certain of the cables when the load is unevenly distributed.

In testimony whereof, we affix our signatures.

ARTHUR D. LIGHTNER.
EDWARD HOLMES.
